UNITED STATES PATENT OFFICE.

FRANK W. BEMM, OF MILWAUKEE, WISCONSIN, ASSIGNOR TO OTTO G. STOFFREGEN,
OF CHICAGO, ILLINOIS.

LINGERIE CLASP.

Application filed May 25, 1927. Serial No. 193,970.

The invention relates to lingerie clasps and more particularly to that type which is provided with a pin whereby the clasp may be attached to the dress, waist or outer garment of the wearer to prevent it from slipping down the lingerie straps or off the shoulder.

One object of the present invention is to provide a clasp of this type in which the attaching pin is of the "safety" variety and is 10 pivotally connected to the top bar of the clasp so that it may be swung laterally thereunder when the wearer desires to use the clasp without the pin.

Another object of the invention is to provide a clasp of the aforementioned character in which the pivotal connection for the attaching pin is at the side of the top bar and is disposed beneath the upper surface thereof so that neither the connection nor the pin will 20 be exposed to abrade the outer garment of the wearer when the pin is in its inoperative position.

A further object of the invention is to provide a lingerie clasp which is of new and improved construction and may be manufactured at a comparatively low cost.

The invention consists in the several novel features hereinabove set forth and more particularly defined by the claims at the conclusion hereof.

In the drawing: Fig. 1 is a perspective of a clasp embodying the invention. Fig. 2 is a cross-sectional view through the central portion of the clasp, the attaching pin being 35 shown in its operative position. Fig. 3 is a view similar to Fig. 2, the pin being shown in its inoperative position.

The invention is exemplified in a clasp comprising a flat metal loop 5 which is adapted to receive and hold together a plurality of lingerie shoulder straps, as well understood in the art. Loop 5 consists of a bottom bar 6 and a top bar 7 which is connected at one end thereof to the bottom bar by a bowed end portion 8. The other end of top bar 7 is curved as at 9 to form a hook-portion 10 which is adapted to be sprung around a curved seat 11. The latter is formed at the free end of bottom bar 6.

50 The clasp also comprises a pin 12 which is connected to top bar 7 as hereinafter described and is adapted to be attached to the dress, waist or outer garment of the wearer to prevent the clasp from slipping down the lingerie straps or off the shoulder. Pin 12 is

of the "safety" variety and consists of a strip of wire which is bent to form a pin-member 13, a connecting loop 14 and a retaining member 15. A head 16 is secured to the free end of member 15 and is provided with a guard or catch 17 for receiving the pointed end of pin-member 13 when the latter is in its closed position. Pin 12 is connected to top bar 7 by a tongue 18 which is formed as an integral part of said bar and projects laterally from one of the side margins thereof. Tongue 18 is bent inwardly and around the head retaining member of pin 12 to form a pivotal connection. This connection permits the pin to be swung from its operative position (Figs. 1 and 2) to an inoperative position (Fig. 3) under top bar 7 when the wearer desires to use the clasp without the pin. A characteristic of the specific pivotal connection disclosed is that neither the connection nor the pin is exposed to abrade the outer garment of the wearer when the pin is in its inoperative position. The bottom and top bars of the clasp are spaced apart when in closed position a distance which is shorter than the width of pin 12. Thus when the pin is in its inoperative position it will be locked against displacement.

The clasp is applied by separating bars 6 and 7 and inserting the lingerie shoulder straps therebetween. The bars are then sprung back into their closed position and pin 12 is inserted into the seam of the wearer's outer garment to secure the clasp in place. In this position, the clasp prevents the straps from slipping off the shoulder. If the wearer does not desire to use pin 12, the latter may be swung out of the way under top bar 7 by first separating the bars.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A clasp of the character described comprising a flat metal retaining loop having a top bar, a tongue connected to said top bar and projecting laterally therefrom, and a safety pin pivotally connected to the tongue.

2. A clasp of the character described comprising a retaining loop having a top bar, a safety pin, a pivotal connection between said

pin and loop, said connection being formed to permit the pin to be swung laterally under the top bar.

3. A clasp of the character described comprising a retaining loop having separable top and bottom bars, a safety pin, a pivotal connection between said pin and loop for permitting the pin to be swung laterally under

the top bar, the distance between said bars being shorter than the width of the pin so ¹⁰ that the pin may be locked under the top bar when the bars are held in connected relation.

Signed at Milwaukee, Wisconsin, this 21st day of May, 1927.

FRANK W. BEMM.
